W. G. BOTTOM,
AUTOMATIC FIRE EXTINGUISHING APPARATUS,
APPLICATION FILED JAN. 13, 1919.

1,379,615.

Patented May 31, 1921.

UNITED STATES PATENT OFFICE.

WILLIAM G. BOTTOM, OF KANSAS CITY, MISSOURI.

AUTOMATIC FIRE-EXTINGUISHING APPARATUS.

1,379,615.

Specification of Letters Patent. Patented May 31, 1921.

Application filed January 13, 1919. Serial No. 270,954.

To all whom it may concern:

Be it known that I, WILLIAM G. BOTTOM, a citizen of the United States, residing at Kansas City, in the county of Jackson and 5 State of Missouri, have invented certain new and useful Improvements in Automatic Fire-Extinguishing Apparatus; and I do hereby declare the following to be a full, clear, and exact description of the invention, 10 such as will enable others skilled in the art to which it appertains to make and use the same.

This invention relates to automatic fire extinguishing apparatus of that kind in 15 which a smothering gas is generated and discharged directly at the place of combustion or on the body of burning or other material.

The principal object of my invention is to 20 provide for automatically and instantly generating a non-oxidizing or smothering gas which is heavier than air, and which can be discharged at the place of combustion or caused to flow over or on the surface of a 25 body of burning material or other material not ignited, such as oil or other highly inflammable material and quench the fire, or prevent combustion.

One of the special objects is to provide 30 for quickly generating a fire extinguishing gas or vapor by heating a chemical solution in a tank and expelling or discharging such gas under the pressure of generation over or upon burning material rather than applying liquid to such material.

Another object is to provide automatically 35 movable means for keeping an electric heating coil immersed in the diminishing body of chemical liquid from which the extinguishing gas is generated, so that the generation of gas will be substantially uniform, and so that the coil shall not be burned out by the current due to exposure out of the liquid.

45 The matter constituting my invention will be defined in the claims.

I will now describe the details of construction and operation of my invention by reference to the accompanying drawings in 50 which:

Figure 1 represents diagrammatically and in plan part of a room and a tank to con-

tain oil and my generating and extinguishing apparatus.

Fig. 2 represents, on enlarged scale, a vertical section of my fire extinguishing apparatus.

In fire extinguishing apparatus now in use the chemical agent is commonly thrown upon a surface which must be hot enough 60 to gasify the chemical or no gas will be generated, and often the fire will gain headway before an extinguishing gas is generated by the burning material in sufficient volume to extinguish the flame. In the case 65 of oil fires or gasoline fires where there is a large surface burning and the flame has not heated parts of the surface on which the chemical in liquid form can be thrown, such chemical sinks into the inflammable liquid 70 and is not effective to arrest combustion. By my method of generating a fire extinguishing gas or vapor in a tank and discharging it upon the burning or inflammable material, combustion can be promptly stopped, and that portion which is not ignited 75 will be prevented from burning. The fire extinguishing action is automatic by reason of the fact that, when a fire is started in a building or in a tank of oil, the heat will 80 melt a fusible link in a line wire, thereby releasing a switch and permitting an electric current to pass into an electric heater in a gas generating tank containing a chemical solution which by heat will yield a smothering gas. The initial heat of combustion 85 acts automatically to start generation of a smothering gas through the medium of an electric current.

I provide a container tank or reservoir A, 90 which may be made of metal, and have at the top a filling opening *a* for a chemical solution, such as carbon tetrachlorid or other chemical from which may be evolved a heavy non-inflammable or smothering gas 95 or vapor. A filling opening *a*, having a cap *a'*, is provided in the top of the tank. With the top of the tank is connected a gas outlet pipe *a''* which may connect with a pipe system K extending through a building. 100 Branch pipes *k*, *k'* lead from pipe K to oil tanks or other stores of combustible material.

A float B, about the diameter of the tank,

is provided for resting on the surface of the liquid and carries at its under side a resistance heating coil C. One or more such coils may be secured to the float. Wires c, c connect the ends of the coil to the sliding contact pieces b, b, which are secured to the top of the float and bear on the electric conductors D, D'. These conductors project vertically on opposite sides of the tank and nearly to the bottom thereof, and have connected to their lower ends the insulating blocks E, E', resting on the bottom of the tank. To the conductors D, D', are connected by binding screws d the line wires f', f''. 15 A line wire f leads from a source of electrical energy F, as a battery, and connects with a switch block g in a bracket or box H. A pivoted switch bar G on a post g' is adapted to make contact with block g and has connecting with its upper end a spring h which is attached to the box H. A line-wire f' connects with the switch and with the conductor D'. 20

A fusible link L is connected in a line-wire l which is attached to the switch bar G to hold it open against the action of the spring h. A line-wire l' connects to the link L and leads to another part of a building, and may have connected in it a number of fusible links L so as to provide for melting a link wherever a fire may occur in a building and thus release the switch bar G. 25

The operation is very simple and practically automatic, for, almost as soon as a blaze starts in any part of a building or in a body of oil, one of the fusible links L will be melted, thereby releasing the switch bar G, which will be pulled by spring h against the block g, establishing electric connection with the battery F and causing current to pass through the heating coil C. Gas will be immediately generated from the chemical solution in tank A and will flow out under pressure through the pipe a'' and be discharged through a branch pipe k or k' upon the fire, as in a tank N or a pile of boxes P. The gas being heavier than oil or gasolene simply covers the fire with a blanket of non-inflammable gas which excludes oxygen and smothers and extinguishes the fire. 40

When the float descends by reason of the liquid M being gasified, it will finally rest upon the insulators E, E', and break the electric circuit, thus stopping generation of gas and preventing the coil from being burned out. It will be understood that the float may be of metal. 45

The tank will be made large enough to hold an adequate supply of liquid to meet the requirements, according to the conditions present. 50

The action of the apparatus is prompt

and efficient and has given satisfaction in practical use. 65

Having thus described my invention, what I claim and desire to secure by Letters Patent is:

1. An automatic fire-extinguishing apparatus, comprising a receptacle adapted to contain a chemical liquid capable of yielding a non-combustible gas, a movable heater in the liquid and adapted to move downward as the liquid is gasified so as to remain immersed, means for automatically supplying by heat of a fire an electric current to the heater and a discharge pipe for gas leading from the receptacle above the chemical substance, whereby the gas may be discharged upon burning or combustible material. 75

2. An automatic fire-extinguishing apparatus, comprising a receptacle adapted to contain a chemical liquid capable of yielding a non-combustible gas, a movable electric heater immersed in the liquid, means for carrying said heater and adapted to move downward as the liquid is gasified, so that the heater will remain immersed, means for automatically supplying by heat of a fire electric current to the heater, and a discharge pipe and connection for gas leading from the receptacle above the liquid. 85

3. An automatic fire-extinguishing apparatus, having a receptacle adapted to contain a chemical liquid capable of yielding a non-combustible gas, a float in the receptacle carrying an electric heating coil and having sliding contact pieces connecting with the coil, vertical electric conductors upon which said pieces bear, a gas discharge pipe above the float and means for automatically supplying by heat of a fire current to the electric heater. 95

4. An automatic fire-extinguishing apparatus, comprising a receptacle adapted to contain a chemical liquid capable of yielding a non-combustible gas, vertical electric conductors in the receptacle and having insulators at their lower ends, a float carrying an electric heater, contact pieces connecting with the heater and bearing on said conductors, means for supplying current to the heater and means actuated by heat of a fire for turning on the current and a gas discharge pipe leading from the receptacle and connecting with branch pipes leading to a store or stores of combustible material, whereby a smothering gas may be spread in blanket form over said material. 100

5. An automatic fire extinguishing apparatus, comprising a receptacle containing a chemical liquid capable of yielding a smothering gas or vapor, an electric heater in con- 115

tact with said liquid for converting it into gas, a gas discharge pipe leading from the top of the receptacle and extending into a compartment of a building, a line wire, 5 having one or more fusible links, also extending into said compartment, a spring actuated switch connecting with said line wire, a source of electrical energy and con-

ductors connecting therefrom to the switch and to the electric heater, whereby, in case 10 of fire in the compartment, said link will be fused, the switch released and a current passed to the electric heater, thereby generating a smothering gas or vapor.

In testimony whereof I affix my signature. 15
WILLIAM G. BOTTOM.
